UNITED STATES PATENT OFFICE.

ROBERT F. GOWEN, OF OSSINING-ON-HUDSON, NEW YORK.

DESIGN FOR A TONGS.

Application filed March 27, 1925. Serial No. 12,910. Term of patent 7 years.

To all whom it may concern:

Be it known that I, ROBERT F. GOWEN, a citizen of the United States, residing at Ossining-on-Hudson, county of Westchester, State of New York, have invented a new, original, and ornamental Design for Tongs, of which the following is a specification, reference being had to the accompanying drawing, forming part thereof.

The single figure of the drawings shows a perspective view of a tongs, showing my new design.

I claim:

The ornamental design for a tongs, as shown.

In testimony whereof, I have affixed my signature hereto.

ROBERT F. GOWEN.
